CENTRAL HEATING BOILER

Julius Vilhelm Gudmand-Høyer and Einar Kamilo Demandt Hansen, Odense, Denmark; said Hansen assignor to said Gudmand-Høyer

Application November 27, 1937, Serial No. 176,782
In Denmark December 14, 1936

3 Claims. (Cl. 122—162)

The invention relates to central-heating boilers of the art consisting of several interconnected water-filled units.

The invention has for its objects firstly to enable each of the units to be manufactured independently from the other units, and consequently, to be removable from the boiler for repairing or inspecting purposes without necessity of setting the boiler as a whole out of operation for this reason; secondly to create a boiler of the art specified in which a very large grate area can be used in order to enable the burning of all kinds of fuel, also such having only a low calorific value, hereby making the boiler specially fitted for horticultural use or the like, where great lots of fuel with low calorific power is available; thirdly to create a boiler with a very great fuel magazine, which can stand unattended for a long time, the construction being so, that 20 the ash produced will not stop the air from having access to the burning fuel.

With these and other objects in mind an embodiment of a boiler in accordance with the invention shall be described under reference to the drawing, on which

Fig. 1 shows a vertical section of the boiler, and Fig. 2 the same in plan view, with the cover removed.

The boiler shown consists mainly of four units, viz. an outer water jacket 1, an inner water jacket 2, and a pipe basket 3 with collecting chamber forming a part of the fuel magazine proper 4 with water-filled walls. The space encircled by the inner water jacket 2 is closed, at the bottom, by a grate 5, while the annular space 6 between the two water jackets is connected at the bottom to the chimney flue 7 and, at the top, to the space 8 encircled by the inner water jacket, in which space the pipe basket 3 is inserted. The pipe basket consists of more superimposed water-filled pipes forming a grate like construction interconnecting, vertical collecting chambers 3'. The pipe basket may be made in one or more parts. The fuel magazine is fitted, at the top, with an opening that can be closed by means of a cover 9. The boiler itself can be closed, at the top, by means of a cover 10, and it rests at the bottom on a footing 11.

The outer water jacket 1 is connected to a return pipe 12 terminating at the bottom in the water jacket, and also by means of a nipple 13 at the top of the water jacket 1, to a collecting chamber 14 disposed outside of the boiler. By means of pipes 15 which also serve to support the grate 5, the said collecting chamber is con-

nected at the bottom to the inner water jacket 2, in that the pipes 15 are connected to nipples 16 on the said water jacket, by means of pipe joints 17 disposed outside of the boiler. The inner water jacket 2 is further fitted, at the top, with pipe nipples 18, which by means of pipe joints 19 are connected to pipes 20 leading to an outlet box 21.

The two water jackets 1 and 2 form a group of units connected to the return pipe on the one side and to the outlet box on the other side. They form thus a separate closed circuit.

The collecting chamber 14 has further two pipe nipples 22 which by means of pipe joints 23 are connected to two pipe nipples 24 leading into the bottom of the pipe basket 3. The latter is fitted, at the top, with pipe nipples 25 which by means of pipe joints 26 are connected to pipes 27 leading up to the collecting box 21. The pipe basket 3 forms thus in the boiler an independent member connected on the one side to the collecting box 14 and, on the other side, to the collecting box 21. In the same manner, the water-filled walls 4 in the fuel magazine are similarly connected to the collecting box 14, and respectively, 20 to the collecting box 21, by means of pipes 28 and 29 and pipe joints 30 and 31, in such a manner that also these walls form an independent unit in the boiler.

The boiler is further, in a manner known per 30 se, fitted with dampers and gates for the supply of primary and secondary air as well as for cleaning for ash, slag and soot.

It is seen that all the pipe joints 17, 19, 22, 26, 30 and 31, by means of which the units of the 35 boiler are interconnected, are situated outside of the boiler so as to be easily accessible, in such a manner that the units can easily be taken apart. It will thus especially easily be feasible to disconnect and remove the fuel magazine 4 and the pipe basket 3, without the boiler having 40 therefore to be set out of operation.

Further it is seen that the fuel filled in the magazine can first burn on the grate proper 5. When this is clogged by ash the air has 45 access to the burning fuel through the openings between the pipes in the pipe basket 3. The filled magazine therefore can stand unattended for a long time.

We claim:

1. A heater, comprising an outer cylindrical water jacket, an inner cylindrical water jacket disposed concentrically within said outer jacket in spaced relationship to the latter so as to provide an annular flue therebetween, a grate clos- 55

ing the bottom of said inner jacket, a fire box basket including a plurality of vertical water pipes projecting upwardly from said grate and being disposed at spaced intervals on a circle
5 having a diameter less than that of said inner water jacket, said grate having some of its perforations outside of said circle, and a plurality of circular tubes supported in superposed spaced relationship on said vertical pipes and interconnected therewith, and a fuel magazine including an innermost cylindrical water jacket having a diameter less than that of the fire box basket and projecting from above into the latter.

2. A heater, as claimed in claim 1, comprising further pipes interconnecting said water jackets and basket pipes and including joints disposed outside of said outer jacket.

3. A heater, as claimed in claim 1, comprising further water collecting chambers, pipes interconnecting said water jackets, basket pipes and collecting chambers, and joints for said pipes, said collecting chambers and joints being disposed outside of said outer jacket. 10
